SLITTING FIXTURE FOR PISTON RINGS

Joseph C. Linn, Hagerstown, Ind., assignor to
The Perfect Circle Company, Hagerstown, Ind.,
a corporation of Indiana

Application October 11, 1929, Serial No. 398,835

5 Claims. (Cl. 90—59)

My invention relates to a slitting fixture for piston rings and more particularly to a device of this kind for holding a previously slit ring during a succeeding slitting operation.

- 5 The principal object of my invention is to devise a fixture of the foregoing character which is constructed and arranged to compress a ring sufficiently to close the preliminary slit by applying a constraining pressure to the major portion of the length of the outer, circumferential surface of the ring, while positively holding the ring in the region of the slit and in directions transverse to and in the plane of the ring against the pressure exerted by the cutting saw.
- 10 15 A further object is to devise a fixture of the character described in which the pressure in the region of the slit can be quickly applied and released, and in which the pressure is so directed as to substantially wedge the indicated portions of the ring against the fixture to positively seat and hold the same.

20 My invention is directed toward providing a fixture for holding a single and previously slit piston ring for presentation to a cutting saw for effecting either a finished slit, or generally, a succeeding slit of some kind. It comprehends a fixture in which a ring is manually placed in position, although it could be mounted by any desired mechanical arrangement without affecting the central thought involved, and in which the tendency of the ring to move in the comparatively, flexible region, adjacent the slit, is completely prevented by applying a suitable pressure in those localities, so disposed as to immobilize the indicated portions of the ring in all directions. The clamping member which effects the foregoing pressure is actuated through a very limited range of movement, from retracted to gripping position, which serves to 25 30 35 40 decrease the time required for positioning the ring.

These and further objects of my invention will be set forth in the following specification, reference being had to the accompanying drawings, and the novel means by which said objects are effectuated will be definitely pointed out in the claims.

In the drawings:

50 Figure 1 is a front elevation of my improved slitting fixture, showing a piston ring positioned therein and a cutting saw in operative relation thereto;

55 Fig. 2 is a section along the line 2—2 in Fig. 1 looking in the direction of the arrows;

Fig. 3 is a plan view of the fixture as viewed in Fig. 1;

Fig. 4 is a sectional view similar to that shown in Fig. 2, but showing several parts of the fixture in retracted positions and in readiness for the receipt of a piston ring;

Fig. 5 is a perspective view of a slitted piston ring such as may be handled by my fixture.

The numeral 10 represents a bedplate which supports an angle bracket 11 whose base 12 is secured to the bedplate 10 by bolts 13. The upstanding portion of the bracket 11 constitutes a face plate 14 having a working face 15 formed on the front, or left edge of the bracket as viewed in Fig. 2. The bracket 11 is slotted as 16 downwardly from the upper edge thereof along a central, vertical line, the separated portions thus formed being strengthened by rearwardly extending ribs 17 disposed on opposite sides of the slot 16 and extending downwardly along the rear side of the plate 14 to the base 12 thereof. Extending forwardly from the face 15, or toward the left as viewed in Fig. 2, is a shoulder 18 having a length substantially equal to the width of the plate 14. Guide plates 19 are secured to the opposite ends of the plate 14 by cap screws 20 and said guide plates extend from the lower edge of the face plate 14 upwardly to the base of the slot 16, said guide plates establishing with the shoulder 18 and the face 15 a recess for a purpose presently explained.

A wedge block 21 is slidably mounted on the shoulder 18 and is provided with an inclined, upper edge 22 and an elongated slot 23 which is parallel to the lower edge of the block. This block is retained against lateral movement by means of a cap screw 24 which extends through the slot 23 for threaded engagement with the face plate 14 and endwise adjustment of said block, for a purpose hereinafter explained, is effected by means of adjusting screws 25 which are threaded through the guide plates 19 and contact with the end edges of the block 21. The right screw 25, as viewed in Fig. 1, effects the desired adjustment of the block 21 toward the left, while the left screw, as viewed in said figure, will effect the desired adjustment in the opposite direction, after which both of said screws may be locked in the indicated positions by means of lock nuts 26.

An adjustable presser block 27 is disposed above the wedge block 21 and is shaped along its lower edge with an inclined surface 28 for engagement with the inclined surface 22 on the block 21. The block 27 is provided with a pair

of spaced, vertically elongated slots 29 through which extend the threaded shanks of cap screws 30 for engagement with the face plate 14. During the vertical adjustment of the block 27, the same is guided by the plate 19, as shown clearly in Fig. 1. The block 27 is bored to form a parti-circular recess 31 which faces upwardly, as viewed in Fig. 1, and which is defined by a parti-annular base 32 and a peripheral shoulder 33, normally disposed with reference to each other, the remaining portion of the recess 31 within the annular base 32 being further bored to a greater depth for purposes of clearance. A pin 35 is fixed in the block 27 midway of the ends thereof and within the margin of the recess 31 for a purpose hereinafter explained.

A block 36 is fixedly secured to the upper portion of the plate 14 by means of cap screws 37 and extends downwardly toward the base of the slot 16. A slot 38 is cut upwardly from the lower edge of the block 36 and so disposed as to be in alignment with the slot 16 when the block 36 is secured in position. The block 36 is further slotted at 39 downwardly from the upper edge thereof in a direction which is inclined to the front face of said block, as shown clearly in Fig. 3, such slot being generally aligned within the limitations of its disposition with the slot 16. The purpose of the slot 39 is to permit the application of a cutting saw 40 to the piston ring 34 as hereinafter described. The block 36 is likewise bored to provide a parti-circular recess 41 which faces downwardly toward and is intended as a complementary recess to the recess 31. The recess 41 is defined by a parti-annular base 42 and a peripheral shoulder 43 normally disposed with reference to each other, the remaining portion of the recess 41 within the annular base 42 being further bored to a greater depth for purpose of clearance. A pin, or cam member 44 is fixed in the block 36 above and in alignment with the vertical, median line of the slot 38. The lower side of the block 36 is cut inwardly from the opposite ends thereof, as is also the face plate 14 immediately above the guide plate 19, to form a pair of slots 63 with each other and with the upper edge of the block 27. These slots extend inward sufficiently to expose portions of the ring 34 in order to permit its easy withdrawal by means of the fingers or a special tool.

The face plate 14 is drilled as at 45 across the slot 16 for the reception of a pin 46 which pivotally supports a lever 47. One end of said lever extends to the rear of the plate 14 and is pivotally connected by means of a pin 48 to one end of a link 49, the other end of said link extending downwardly through suitable holes in the base 12 and bedplate 10 for connection to and actuation by mechanism of a suitable nature, such as a lever, pedal, and the like. The opposite end of the lever 47 extends forwardly of the front face of the block 36 and is provided with a curved nose 50 which extends generally in an upward direction and the rear side of said nose is further defined by a reentrant curve 51.

The nose 50 projects loosely through an elongated slot 52 which is formed within the marginal edges of a clamping member 53 having a generally rectangular shape. The upper end of the slot 52 is inclined as at 54 upwardly and toward the left from the inner face of the member 53 and said inclined surface is normally in contact with the nose 50, both in gripping and

retracted positions. The upper end of the member 53 is bifurcated to provide a pair of arms 55 which are notched inwardly from the inner face of said member to provide a pair of normally disposed faces 56 and 57 intended for contact with separated portions of a flat face of the ring and also the inner, curved face thereof. A portion of the inner face of the member 53, immediately below the aforesaid notches, is offset as at 58 and said offset portion is connected to the remaining area of the inner face of said member by means of an inclined, or cam, surface 59. The lower end of the member 53 is provided with an offset shoulder 61 whose face contacts with the inner portion of the recess 31, 15 operating as a spacing element.

In using the slitting fixture, the block 27 will be adjusted vertically to such a position, dependent upon the size of the ring to be slotted, that when the ring is in position in the fixture, 20 the slit 62 thereof will be substantially closed by the constraining pressure exercised by the peripheral shoulders of the recesses 31 and 41. The rings may be placed within the holder constituted by the blocks 27 and 36 either manually, or by any suitable type of mechanical contrivance. During this initial positioning of the ring, the lever 47 and the clamping member 53 will occupy the positions shown in Fig. 4 and the manner in which said member achieves the 30 position shown will be presently described.

The ring 34 having been positioned in the aforesaid holder with the slit 62 thereof properly disposed with reference to the inclined slot 39, the link 49 will be actuated downwardly to 35 cause an upward movement of the opposite end of the lever 47 with a consequent lifting of the member 53, by reason of the contact between the nose 50 and inclined surface 54, to the position shown in Fig. 1. In this position, the 40 arms 55 will be disposed on opposite sides of the slot 39 and the notched faces 56 and 57 of each arm will bear against certain portions of the outer, flat face of the ring and the curved, inner surface, respectively. It will be observed 45 that, by reason of the inclined disposition of the surface 54 and the direction in which the nose 50 applies pressure to said surface, the notched faces 56 and 57 will be substantially wedged against the contacted portions of the 50 ring to thereby adequately seat the latter within the holder and absolutely prevent any movement thereof adjacent the slit 62. The cutting saw 40 will then be moved toward the fixture, or vice versa as determined by operative conditions, and the slitting operation effected.

After the slit has been cut, the link 49 will be moved upwardly to cause a downward movement of the nose end of the lever 47 and consequently a release of pressure against the inclined surface 54. The clamping member 53 being loosely mounted on the nose end of the lever 47 will thereupon begin to move downwardly from the position shown in Fig. 2, but it is important to control this downward movement so that said member will finally reach the fully retracted position, shown in Fig. 5. This control is effected by means of the head of the pin 44 which engages with the inclined, or cam surface 59 on the inner face of the member 53, 70 during its downward movement, to thereupon positively throw the upper end of said member outwardly from the face plate, this result being facilitated by the slightly greater thickness which the member 53 has at its upper end, 75

thus creating a slight overhang in this portion of the member. The nose 50 continues to move downwardly and is closely followed by the upper end of the member 53 after actuation by the pin 44, until the lower end of said member engages with the stop pin 35, whereupon further downward movement of said member is arrested and it is retained in the position shown in Fig. 5 with the inclined surface 54 resting on the curved nose 50 and the member as a whole inclining outwardly from the face of the holder.

The member 53, both in its gripping and in its retracted positions is retained wholly within the portion of the holder which is occupied by the piston ring. Accordingly, only short movements are necessary to place said member in either of the indicated positions, so that the movable part of the fixture may be actuated with ease and precision. Due to its loose engagement with the lever 41, the member 53 is at all times in a position for quick removal in the event of any breakage, while the style of clamping member illustrated affords a convenient means of adequately holding a previously slit piston ring in localities adjacent to the slit, which portions are the most flexible of the ring and consequently more subject to movement under the pressure exerted by the cutting saw.

While I have shown one set of elements and combinations thereof for effectuating my improved slitting fixture, it will be understood that the same is intended for purposes of illustration only and in nowise to restrict my device to the exact forms and structures shown, for many changes may be made therein without departing from the spirit of my invention.

I claim:

1. A slitting fixture for a piston ring comprising in combination, a holder for receiving the ring, a lever pivoted on said fixture, a clamping member having a cam surface adjacent the upper end thereof facing said holder and loosely straddling said lever for actuation thereby when moved in one direction to grip said ring on opposite sides of a cutter during the slitting operation, and a pin projecting from the upper face of said holder, said lever permitting the retraction of said member under the action of gravity when moved in the opposite direction, and said pin engaging said cam surface during the retracting movement of said member to throw the upper portion thereof away from the plane of the holder.

2. A slitting fixture for a piston ring comprising in combination, a holder for receiving the ring, a lever pivoted on said fixture, a clamping

member having a cam surface adjacent the upper end thereof facing said holder and loosely straddling said lever for actuation thereby when moved in one direction to grip said ring on opposite sides of a cutter during the slitting operation, a pin projecting from the upper face of said holder, said lever permitting the retraction of said member under the action of gravity when moved in the opposite direction, and said pin engaging said cam surface during the retracting movement of said member to throw the upper portion thereof away from the plane of the holder, and a stop for limiting the downward movement of said member during its retraction.

3. A slitting fixture for a piston ring comprising in combination, a holder for receiving the ring, a lever pivoted on said fixture, a clamping member loosely carried by said lever, the actuation of said lever in one direction serving to grip said member against the ring on opposite sides of a cutter during the slitting operation, and the actuation of said lever in the opposite direction permitting the retraction of said member under the action of gravity, and means for throwing the ring engaging end of said member away from the plane of the holder during the retracting movement of said member.

4. A slitting fixture for a piston ring comprising in combination, a holder for receiving the ring, a clamping member located within the periphery of the ring for gripping the same on opposite sides of a cutter during the slitting operation, a lever pivoted on said fixture and having an arm extending through the plane of said ring within the periphery thereof for controlling the movements of said member to gripping and releasing positions, and means for throwing the ring-engaging portion of said member away from the plane of the holder during the releasing movement of said member.

5. A slitting fixture for a piston ring comprising in combination, a holder for receiving the ring, a lever pivoted on said fixture, and a clamping member loosely carried by said lever, said member being located within the periphery of the ring with one end being adapted to grip the ring on opposite sides of a cutter during the slitting operation and the other end adapted to bear against the face of the holder, the actuation of said lever in one direction moving said member into gripping position and in the opposite direction permitting the releasing movement of said member under the action of gravity.

JOSEPH C. LINN. 55
